UNITED STATES PATENT OFFICE.

STEPHEN I. FEKETE, OF DETROIT, MICHIGAN, ASSIGNOR TO HUDSON MOTOR CAR COMPANY, OF DETROIT, MICHIGAN, A CORPORATION OF MICHIGAN.

TAPPET COVER FOR INTERNAL-COMBUSTION ENGINES.

Application filed July 28, 1923. Serial No. 654,324.

To all whom it may concern:

Be it known that I, STEPHEN I. FEKETE, a citizen of the United States, residing at Detroit, county of Wayne, State of Michigan, have invented a certain new and useful Improvement in Tappet Covers for Internal-Combustion Engines, of which the following is a specification, reference being had thereto in the accompanying drawings.

10 The present invention has for its object an improved cover for the tappet chamber of the cylinder block of an internal combustion engine. In internal combustion engines of the T-head and L-head types, and particularly those in which the cylinders are cast in a single block, the valve tappets are located in a chamber in the side of the casting. This chamber has ordinarily been covered by a cover or covers which are bolted in place. As other parts of the mechanism, such as the carburetor, or the electrical apparatus are usually placed close to the covers, their removal has been an inconvenient matter and in many cases has made 20 the use of a single cover impossible because its length was too great for the space through which it had to be moved. Where two or more covers have been used, the cylinder casting has been formed with a vertical partition or bar to form a support for the proximate edges of the two covers. The tappets are freely lubricated and their movement spatters the oil about the interior of the chamber and against the inside of the 30 covers, so it is essential that there be an oil tight joint between the covers and the cylinder block.

The invention described herein furnishes a single cover for the tappet chamber. This 40 cover extends the entire length of the tappet chamber but can be removed notwithstanding the presence of a carburetor or other obstructions. The invention makes possible an important simplification of the cylinder casting, and reduces its cost because no partition or bar across the tappet chamber is necessary. It also tends to reduce the noise of the engine somewhat by deadening the vibration.

50 The invention will be fully understood from the following description when taken in connection with the accompanying drawings, and the novel features thereof will be pointed out and clearly defined in the claims at the close of this specification.

In the drawings:

Fig. 1 is a side elevation showing the cover embodying my invention in place on an engine block.

Fig. 2 is a side elevation of the cover.

Fig. 3 is a section on line 3—3 of Fig. 2.

Fig. 4 is a section on line 4—4 of Fig. 2.

Fig. 5 shows on a smaller scale the position of the parts when the cover is folded for removal.

In the drawings, the engine block is shown at A. The tappet chamber C is in the usual position and is covered by the tappet chamber cover which is described herein. The tappet chamber cover consists of two parts 70 11 and 12 of the shape shown in Figs. 3 and 4. The parts are hinged together preferably by a flexible imperforate member 13 secured to the proximate edges of the two halves of the cover. In practice, leather is 75 preferred for this purpose and is held in place by a reinforcement or batten 14 and rivets 15. In practice, the leather is also glued to the parts 11 and 12 before the rivets are inserted thereby ensuring an oil 80 tight joint. The halves of the cover are held in place in the ordinary manner, that is by nuts 17, secured to studs 18, which pass through holes 19 in the halves of the cover. The upper, lower and outside end edges rest 85 upon the seats formed on the cylinder block casting, but the two proximate edges do not require any support being hinged together by the flexible member 13. As already explained this does away with the necessity 90 for a vertical partition or bar which would otherwise be placed behind the inner vertical edges of the halves of the cover, and which adds considerably to the expense of the cylinder casting, and interferes with the 95 accessibility of the tappets and valves.

At 20 is shown the usual oil shield of sheet metal which deflects away from the joint the oil which runs from the inside face of the cover.

When the cover is to be removed, the nuts 17 are taken off and then one half 11 is swung on the hinge formed by the flexible member 13, thus shortening the over-all length of the cover and permitting it to 100 be moved toward the dashboard or radiator as the case may be and thus taken out even though the carburetor is in the way and would prevent the removal of a unitary 105 structure.

What I claim is:

1. The improved cover for the tappet chamber of the cylinder block of an internal combustion engine which comprises two halves formed of metal and secured together by a hinge which unites their proximate edges.
2. In combination with the cylinder block of an internal combustion engine having a tappet chamber on the side, a cover for said chamber comprising two halves hinged together along their proximate edges.
3. The improved cover for the tappet chamber of the cylinder block of an internal combustion engine which comprises two halves secured together by an imperforate hinge of flexible material.
4. The improved cover for the tappet chamber of the cylinder block of an internal combustion engine which comprises two metallic halves and a hinge of leather.

In testimony whereof I affix my signature.

STEPHEN I. FEKETE.
